The ornamental design for a carrying bag, as shown and described.

DESCRIPTION

FIG. 1 is a front perspective view of a carrying bag showing my new design;

FIG. 2 is a top view of the carrying bag of FIG. 1;

FIG. 3 is a left side view of the carrying bag as shown in FIG. 1;

FIG. 4 is a front elevational view of the carrying bag of FIG. 1;

FIG. 5 is a rear elevational view of the carrying bag as shown in FIG. 1;

FIG. 6 is a right side view of the carrying bag of FIG. 1;

FIG. 7 is a bottom view of the carrying bag as shown in FIG. 1;

FIG. 8 is a front perspective view of the carrying bag as shown in FIG. 1 with the top lid opened showing the interior of the bag;

FIG. 9 is a top view of the carrying bag as shown in FIG. 1 with the lid opened showing the interior of the lid and of the bag;

FIG. 10 is a front perspective view of the carrying bag as shown in FIG. 1 with the front lower right compartment cover opened showing the interior of the compartment; and, FIG. 11 is a front elevational view of the carrying bag as shown in FIG. 10 with the front lower right compartment cover opened showing the interior of the compartment.

The areas of cross-hatching are meant to represent a texture that extends across the entire surface.
